US0D1061447S

(12) **United States Design Patent** (10) **Patent No.:** **US D1,061,447 S**
(45) **Date of Patent:** **** Feb. 11, 2025**

(54) **CONNECTOR**

(71) Applicant: **Winchester Interconnect**, Norwalk, CT (US)

(72) Inventor: **John E. Benham**, Norwalk, CT (US)

(73) Assignee: **Winchester Interconnect**, Norwalk, CT (US)

(**) Term: **15 Years**

(21) Appl. No.: **29/872,663**

(22) Filed: **Mar. 16, 2023**

(51) LOC (15) Cl. **13-03**

(52) U.S. Cl.

USPC **D13/146; D13/133**

(57) **CLAIM**

The ornamental design for a connector, as shown and described.

DESCRIPTION

FIG. 1 is a perspective view of the top, front, and left side of the connector;

FIG. 2 is a perspective view of the bottom, front, and right side of the connector;

FIG. 3 is a front view of the connector;

FIG. 4 is a rear view of the connector;

FIG. 5 is a left side view of the connector;

FIG. 6 is a right side view of the connector;

FIG. 7 is a top view of the connector; and,

FIG. 8 is a bottom view of the connector.

The broken lines shown in the figures are for the purpose of illustrating portions of the connector that form no part of the claimed design.

1 Claim, 8 Drawing Sheets
